UNITED STATES PATENT OFFICE.

KARL BAUMANN, OF URMSTON, AND ARTHUR EDWIN LEIGH SCANES, OF ASHTON-ON-MERSEY, ENGLAND, ASSIGNEES TO THE BRITISH WESTINGHOUSE ELECTRIC AND MANUFACTURING COMPANY LIMITED, A COMPANY OF GREAT BRITAIN.

CONDENSING-STEAM-TURBINE INSTALLATION.

1,372,930.

Specification of Letters Patent. Patented Mar. 29, 1921.

Original application filed January 31, 1917, Serial No. 145,709. Divided and this application filed December 28, 1920. Serial No. 433,724.

To all whom it may concern:

Be it known that we, KARL BAUMANN, a citizen of the Confederation of Switzerland, and a resident of Urmston, in the county of 5 Lancaster, England, and ARTHUR EDWIN LEIGH SCANES, a subject of the King of Great Britain, and a resident of Ashton-on-Mersey, in the county of Chester, England, have invented a new and useful Improvement 10 in or Relating to Condensing-Steam-Turbine Installations, which is a division of application Serial No. 145,709, filed January 31, 1917, and of which the following is a specification.

15 In condensing steam turbine installations it has already been proposed to divide up the steam flowing from the last row or rows of blades of the turbine to the condenser by means of guide walls, diaphragms or the like located in the exhaust casing of the turbine, and the present invention relates to condensing steam turbine installations in which the exhaust casing of the turbine is provided with such guide walls, diaphragms 20 or the like, and has for its object to provide an improved construction and arrangement of condenser for use with a turbine of the above kind.

25 In a surface condenser the temperature of the water flowing through the condenser tubes varies, and as the rate of condensation depends upon the temperature difference between the steam and temperature of the water, the cooler portions of the condenser will condense more steam than the hotter portions, with the result that in an installation comprising a turbine and a surface condenser there is a tendency for steam to be drawn by the cooler condensing surface 30 from portions of the exhaust outlet of the turbine other than those portions located immediately above the cooler condensing surface. This tends to increase the length of the path of the steam flowing to the condenser and to increase the pressure drop accordingly. A similar effect is also observable in condensers of the jet or direct contact type.

35 In order to obviate this difficulty, according to the present invention some or all of the aforesaid guide walls, diaphragms or the like, in the exhaust casing of the turbine are

continued beyond the exhaust outlet of the turbine through into the condenser itself in such a manner that the condenser is divided 55 up into a number of compartments each of which will act as a separate condenser.

Stated in another way, the condenser is provided with partitions or the like adapted to form continuations of some or all of the 60 guide walls, diaphragms or the like in the exhaust casing of the turbine, which partitions divide up the condenser into a plurality of compartments in such a manner that each of said compartments will act as a 65 separate condenser.

In order to obtain approximately equal condensation in each compartment of the condenser thus formed the flow of cooling water is preferably so arranged that in case 70 of a surface condenser the temperature of the water in the tubes in each of the compartments is as uniform as possible. This may be accomplished by arranging that the water will flow once only through each compartment. Each compartment will in this way constitute in effect a single flow condenser, but although in this way the temperature of the water in each compartment of the condenser is rendered as uniform as 75 possible, the temperature of the water in the several compartments of the condenser will differ.

80 Several constructional forms which the invention may take are illustrated by way 85 of example in the accompanying drawings in which Figure 1 is a vertical section on line 1—1 of Fig. 2 through the exhaust casing of a turbine and a condenser, the latter being constructed in accordance with this 90 invention.

Fig. 2 is a sectional view taken on the line II—II of Fig. 1.

Figs. 3 and 4 are fragmentary views on an enlarged scale and Fig. 5 a view on the same 95 scale taken on the lines III—III, IV—IV and V—V, respectively of Fig. 2.

Figs. 6 and 7 are diagrammatic views of a turbine and of a condenser, the latter constructed in accordance with this invention 100 in which the area of the condensing surface of the compartments into which the condenser is divided varies.

Figs. 8 and 9 are diagrammatic views

showing how the invention may be applied to condensers of the direct contact or jet type.

Referring now to Figs. 1 to 5, the exhaust casing 1 of the turbine is provided with a diaphragm of the kind fully described and illustrated in the specification of British Patent No. 2,848 of 1914. The condenser 2 is furnished with a central partition wall 3 which extends to and forms joint with the guide wall 4 in the turbine exhaust and the point of junction of the V shaped containing walls 6, 6 of the exhaust casing of the turbine. The condenser is also provided with a longitudinal partition wall 7, which extends upward till it meets the lower edge of the diaphragm 8 extending across the exhaust casing of the turbine. For a purpose herein-after explained both the partition walls 3 and 7 extend downward into the condensate extraction chamber 9 from which the usual condensate discharge outlet 10 leads to the extraction pump 11. In this way the condenser is divided into four separate compartments. As shown in Figs. 3 and 4, the walls 6, 6 as well as the wall 4 should be carried right up to the last row of moving blades 12 so that only a small clearance exists between said walls and the moving blades in order to prevent leakage from one compartment of the exhaust casing into another. The same is true also of the diaphragm 8 where it adjoins the moving blades 12. From the drawings, it will be seen that the diaphragm and partition members of the exhaust casing extend closely adjacent to the last row of moving blades and transversely to the plane of rotation thereof, whereby the annulus of steam discharged therefrom is immediately divided up into a plurality of arcuate portions. The water inlet to the condenser is shown at 13 and the water outlet at 14, the condenser here shown, as will be readily perceived, being of the double flow type. Hence the water flows in one direction only through each of the four compartments into which the condenser is divided by the partition walls 3 and 7.

It will be seen that we have devised an arrangement whereby the steam discharged from a last row of blades is divided and led to independent portions of a condenser. In Figs. 6-9 inclusive, the steam discharged is divided into two paths, whereas in Figs. 1-4, inclusive, the steam is divided into four paths. We prefer to divide the condenser into four condensing portions, two portions being arranged near the plane of the last row of blades and the other two being arranged farther away. With this arrangement, the steam discharged from the last row of blades may be divided into four portions, the two lower portions being discharged by curved passageways into the condenser portions near the plane of the last row of blades and

the upper portions of steam being conducted by passageways curved over the lower-portion passage-ways to the other condensing portions.

As hereinbefore set forth, the important feature of our invention is the division of the exhaust of a plurality of portions and leading each portion to an independent condensing portion of a condenser. The presence of diaphragms in the exhaust casing to divide the exhaust facilities the passage of the latter to the condenser with smaller eddy losses than ordinarily. The division of the condenser into a plurality of independent condensing portions is responsible for condensation taking place more uniformly and with a slight drop in pressure of the steam and non-condensable gases and vapors.

While we have shown my invention in a number of forms, it will be obvious to those skilled in the art that it is not so limited but is susceptible of various other changes and modifications, without departing from the spirit thereof and we desire, therefore, that only such limitations shall be placed thereupon as are imposed by the prior art or as are specifically set forth in the appended claims.

What we claim is:—

1. A power installation comprising a steam turbine, a condenser, partitions for dividing the condenser into a plurality of independent condensing portions, an exhaust casing for the turbine communicating with the condenser, and partition or diaphragm members for dividing the discharge of the last row of moving blades into a plurality of portions and co-operating with the exhaust casing and the condenser partitions to define continuous passageways to the independent condensing portions for the divided portions of steam.

2. A power installation comprising a turbine, a condenser disposed transversely of the turbine axis, a portion dividing the condenser into independent condensing portions, an exhaust casing for the turbine, and partition or diaphragm members for dividing the discharge of the last row of blades into a plurality of portions and co-operating with the casing and the condenser partition to define continuous passageways for conducting each steam portion to an independent condensing portion.

3. A power installation comprising a turbine, a condenser, partitions for dividing the condenser into a plurality of independent condensing portions, an exhaust casing for the turbine communicating with the condenser, and partition or diaphragm members extending close to the last row of moving blades and transversely to the plane of rotation thereof for immediately dividing the annulus of steam discharged therefrom into a plurality of arcuate portions and co-

operating with the exhaust casing and the condenser partitions to define continuous passageways to the independent condensing portions for the divided portions of steam.

5. 4. A power installation comprising a turbine, a condenser, partitions for dividing the condenser into a plurality of condensing portions, an exhaust casing for the turbine communicating with the condenser and partition members carried by the casing for dividing the exhaust of the last row of blading into two upper portions and two lower portions and coöoperating with the casing to define continuous passageways for each steam portion to an independent condenser portion, the passageways for the upper portions being curved over the passageways for the lower portions.
5. A power installation comprising a turbine, a condenser arranged cross-wise of the turbine axis, partitions for dividing the condenser into four condensing portions, two

portions being spaced farther away from the plane of the last row of blades than the other two portions, an exhaust casing for 25 the turbine communicating with the condenser, partition members carried by the casing for dividing the exhaust of the last row of blades into two upper portions, and two lower portions and coöoperating with the 30 casing to define continuous passage-ways for each portion to an independent condenser portion, the passageways for the lower portions discharging into the condenser portions nearer the plane of the last row of blades 35 and the passageways for the upper portions being curved over the passageways for the lower portions and discharging into the other condenser portions.

In testimony whereof, we have hereunto 40 subscribed our names this 29th day of October 1920.

KARL BAUMANN.
ARTHUR EDWIN LEIGH SCANES.
